(57) **CLAIM**

The ornamental design for a earphones with charging case, as shown and described.

DESCRIPTION

FIG. 1 is a front, right, and top perspective view of earphones with charging case showing the new design; FIG. 2 is a front, right, and top perspective view of the charging case, of earphones with charging case, shown separately for ease of illustration;

FIG. 3 is a rear, left and bottom perspective view thereof;

FIG. 4 is a front view thereof;

FIG. 5 is a rear view thereof;

FIG. 6 is a left side view thereof;

FIG. 7 is a right side view thereof;

FIG. 8 is a top plan view thereof;

FIG. 9 is a bottom plan view thereof;

FIG. 10 is a front, right, and top perspective view of the charging case of earphones and charging case in an open position thereof;

FIG. 11 is a rear, left and bottom perspective view thereof;

FIG. 12 is a front, right, and top perspective view of earphones of the earphones with charging case, shown separately for ease of illustration;

FIG. 13 is a rear, left and bottom perspective view thereof;

FIG. 14 is a front view thereof;

FIG. 15 is a rear view thereof;

FIG. 16 is a left side view thereof;

FIG. 17 is a right side view thereof;

FIG. 18 is a top plan view thereof; and,

FIG. 19 is a bottom plan view thereof.

The broken lines shown in the drawings illustrate portions of the earphones with charging case that form no part of the claimed design.

1 Claim, 19 Drawing Sheets
